INVENTOR,

Douglas Brews

By Fisher & Moore, Atty.

UNITED STATES PATENT OFFICE.

DOUGLAS BREWS, OF CLEVELAND, OHIO.

FEED-WATER HEATER.

No. 891,399.

Specification of Letters Patent.

Patented June 23, 1908.

Application filed November 11, 1907. Serial No. 401,577.

To all whom it may concern:

Be it known that I, DOUGLAS BREWS, a citizen of the United States, residing at Cleveland, in the county of Cuyahoga and State 5 of Ohio, have invented certain new and useful Improvements in Feed-Water Heaters, Purifiers, and Surface Blowers for Steam-Boilers, and do declare that the following is a full, clear, and exact description of the invention, which will enable others skilled in the art to which it appertains to make and use the same.

My invention relates to a feed water heater, purifier and surface blower for steam boilers, 15 and the invention consists in the construction and combination of parts substantially as shown and described and particularly pointed out in the claims.

In the accompanying drawings, Figure 1 20 is a cross section of the front end of the boiler showing my invention in end elevation, and Fig. 2 is a longitudinal sectional elevation of a boiler showing my invention in side elevation.

25 The objects of the invention as thus shown are, first, to heat the feed water; secondly, to purify the same in its passage into the boiler, and, thirdly, to blow off surface accumulations from the water in the boiler.

30 Heating of the feed water as a first step in the purifying process is deemed essential because by so doing I more or less disintegrate the foreign particles or substances that are obnoxious but which unavoidably appear in the water and may be more or less in solution or in some form of union or combination therewith and which manifest themselves at last in accretions or scale on the tubes and surface of the boiler, as well as in 35 other objectionable forms, especially if the water be fouled with vegetable, or mineral matter or both, as often occurs. The invention contemplates trapping the mass of foreign matter of substances of all forms that 40 will deposit by gravity, and the removal of floating matter by blowing the same from the surface of the water, thus largely purifying the water before it enters the boiler areas and cleansing it of matter that may escape 45 such initial operations. To these ends I employ the novel construction shown herein, comprising a main feed water pipe P, which has as many joints as may be needed and runs lengthwise of the boiler in the top there-

of in the steam space or area from rear to 55 front, the entrance of the pipe within the boiler being preferably by an elbow or vertical portion 2 extending from about the normal water level to the top portion of the boiler and having a valve control at 4 outside 60 at the end of the boiler. Water being admitted by this line of pipe, it is discharged at the front of the boiler into a vertically disposed tube D, having a reduced lower section d extending down into sediment 65 deposit or trapping chamber C about half way the depth thereof, more or less, and which extension d is sufficiently smaller in cross section than said chamber C to afford an overflow water space between them. The 70 upper end of said chamber or cylinder C is open and rises to about the normal water level in the boiler or just a little below such level, so that the surface water may be blown off through said chamber and the chamber itself 75 is cleansed of its deposits through blow-out pipe E leading therefrom when live steam is driven through the same for these purposes. Said blow-out pipe E discharges out of the rear end of the boiler, where a suitable cock 80 or valve 6 controls the discharge, and connection of said pipe is with the lower end of chamber C. The tube or pipe D is open at both ends, and when cock or valve 6 is opened for blow-out purposes steam passes 85 down through tube D and creates a powerful suction from the surface of the water in the boiler at the top of chamber or cylinder C, draining off said surface and all the floating accumulations therewith. 90

By placing the purifying mechanism at the front of the boiler I avoid the excessive heat at the rear thereof and obtain better results than would be practicable where the heat is excessive. 95

By running tube D down into the chamber C relatively as shown and having said tube of the requisite depth the inflowing feed water strikes the water level at the top of said chamber in tube D, so that deposits in 100 said chamber are not agitated thereby while the water quietly overflows from the top of the chamber. A T shaped coupling 10 is removably affixed to the bottom of the said chamber for connection of pipe E, in order 105 that a man may unscrew the plug 12 therein and run a wire into the chamber, if necessary, to stir the deposits to remove the same.

An elbow 14 appears in pipe P near to tube D which facilitates arrangement of said pipe in respect to said tube.

What I claim is:—

- 5 A steam boiler, a combined surface scumming and blow-off receptacle of tubular shape erected vertically in the front end of the boiler and having its upper end open full width and substantially even with the water
10 level in the boiler, a feed water heater D of tubular form having a relatively reduced lower end immersed in said receptacle and discharging thereto below said water level and having its upper half open full width at

its top and exposed its full depth to the steam 15 in the boiler, a feed water pipe extending lengthwise through the top of the boiler and discharging at its end directly into the open mouth of said feed water heater D, and a valve controlled discharge pipe leading from 20 the bottom of said sediment receptacle.

In testimony whereof I sign this specification in the presence of two witnesses.

DOUGLAS BREWS.
